ATTORNEY

UNITED STATES PATENT OFFICE.

JULIEN STRANDERS, OF NEW YORK, N. Y., ASSIGNOR TO HARRY B. KRUGER, OF NEW YORK, N. Y.

ADVERTISING OR DISPLAY DEVICE.

1,387,209.

Specification of Letters Patent. Patented Aug. 9, 1921.

Application filed March 11, 1918. Serial No. 221,695.

To all whom it may concern:

Be it known that I, JULIEN STRANDERS, a subject of the King of England, and a resident of New York, county of Kings, in the State of New York, have invented certain new and useful Improvements in Advertising or Display Devices, of which the following is a specification.

The present invention relates to advertising or display devices, and particularly such devices to be exhibited in connection with the articles advertised. An object of the invention is to provide such a device which may be combined with the article to be displayed in a manner as to be attractive and to effectually display the same. Another object is to provide such a device which may be formed from a single piece of material without pasting, if desired, will lie flat when not in use, may be quickly set up, and will remain rigidly supported when set up. A further object is to provide a display device which, when combined with the article to be displayed, will give the picture effect of a group of articles in proper perspective and relief. It is also proposed with the present device to enable the article to be first placed in position independently of the display device, and thereupon place the device in display relation therewith.

With these and other objects in view, an embodiment of my invention is shown in the accompanying drawings and this embodiment will be hereinafter more fully described with reference thereto and the invention will be finally pointed out in the claims.

In the accompanying drawings,

Figure 1 is a perspective view showing one embodiment of my invention combined with an article to be displayed;

Fig. 2 is a plan view of the device in flat position and as blanked out;

Fig. 3 is a sectional view taken along the line 3—3 of Fig. 2; and

Fig. 4 is an end view of the device in the set up position shown in Fig. 1.

Similar reference characters indicate corresponding parts throughout the several figures of the drawings.

Referring to the drawings, the display device formed according to the present embodiment of my invention is formed from a single piece of material, preferably card

board, and comprises an upper display panel 55 10 and a lower display panel 11, the said panels being suitably scored or otherwise hingedly formed at their junction 12. The outline of the panel 10 at one of its side edges is preferably such as to conform to the 60 articles displayed therein, thus adding to the realistic visual effect. Also it is preferably of a size to contain suitable advertising phrases descriptive of the articles displayed. The lower edge of the panel 11 is preferably 65 straight and the panel is substantially wider than the article to be displayed.

An opening 13 is provided in the panel 11 adjacent the panel 10 and a portion 14 of the said panel 10 projects from one end of the 70 opening and forms in effect a leg.

In display position, the panel 10 is disposed in a perpendicular position, the leg 14 resting upon the supporting surface and the panel 11 is inclined forwardly and downwardly from the said panel 10, its lower straight edge resting upon the supporting surface. It is to be noted that the main panel 10 and the tongue or extension 14 therefrom respectively engage against the 80 rear side of the article 15 above and below the hinge 12. Thus it will be apparent that the main panel will be at all times maintained in its erect or perpendicular position and its angular deflection in either direction 85 by movement at the hinge 12 is effectively obviated.

The article to be displayed in the present instance, a can 15 of rectangular cross section, is placed in the opening 13 and the display device is thereby rigidly supported in display position, the opening being of a shape conforming to the diagonal cross section of the can at the plane intersected by the panel 11 in its display position. In this 90 manner the device fits the article snugly and the panel 10 is held perpendicularly and in engagement with the article.

The panel 11 affords a space for suitable advertising matter and, by reason of its inclination, this may be easily read.

The device, it will be seen, is simple in construction, may be readily set up and removed from the article to be displayed, and provides a very attractive and effective display.

I have illustrated and described a preferred and satisfactory embodiment of my

invention, but it is obvious that changes may be made therein within the spirit and scope thereof as defined in the appended claims.

I claim:

5 1. A display device comprising a main panel and a secondary panel having a horizontal hinge connection along one of its edges to said main panel, said secondary panel being provided with an article receiving opening extending from one side of the main panel to a point in spaced relation to the free longitudinal edge of the secondary panel, said device adapted for arrangement upon a supporting surface with the main 10 panel vertically disposed and the secondary panel extending forwardly and downwardly at an inclination from the main panel and resting at its free edge upon the supporting surface, the device being retained in display 15 position by the article positioned in the opening of the secondary panel and said main panel having parts contacting with the article above and below the horizontal hinge line connecting the panels to prevent hinging movement of the main panel in either direction with respect to the secondary panel.

2. A display device comprising a one piece structure having a main panel, and a secondary panel having an opening therein to receive an article which rests upon a supporting surface, and the main panel having means engaging the supporting surface to sustain the panel in erect position, said display device being applicable to or removable from its associated position with relation to the article without disturbing the position of the article relative to the support.

3. A display device comprising a vertical main panel and a secondary panel inclined to the vertical main panel, and connected with the vertical main panel at its bottom, having an opening therein to receive an article which rests upon the supporting surface, and the main panel having means coacting with the article to prevent lateral movement of the main panel in a direction away from the article and sustain the panel in erect position, the connection of the main and secondary panels being below the top of the article in the opening.

4. A display device comprising a vertical main panel and a relatively movable secondary panel having an opening therein, and 55 inclined to the vertical main panel, and connected therewith at its bottom, the opening being adapted to receive an article which rests upon a supporting surface, and the

main panel having a leg engaging the supporting surface and coacting with the article to prevent collapse of the device, and sustain the respective panels in their display position, the connection of the main and secondary panels being below the top of the article in the opening.

5. A display device comprising angularly related relatively movable panels, one of said panels having an opening therein through which an article is adapted to be placed to rest directly upon a suitable support, the other panel having means to engage the support and position the first named panel with said opening in spaced relation to the support whereby the display device is sustained in its display position relative to the support, the connection of the main and secondary panels being below the top of the article in the opening.

6. A display device comprising angularly related, hingedly connected panels, one of said panels having an opening therein through which an article is adapted to be placed to rest directly upon a suitable support, the other panel having means to engage the support and position the first named panel with said opening in spaced relation to the support, and the second named panel contacting with the article whereby the device is sustained in its display position relative to the support.

7. A display device comprising angularly related, hingedly connected panels, one of said panels having an opening therein through which an article is adapted to be placed to rest directly upon a suitable support, the other panel having means to engage the support and position the first named panel with said opening in spaced relation to the support, and the second named panel contacting with the article at points above and below said opening whereby the device is sustained in its display position relative to the support.

8. A display device comprising a pair of hingedly connected panels adapted to be arranged in angular relation to each other, one of the panels having an article receiving opening therein, the other of said panels being adapted to engage the article above and below said opening whereby the latter panel is sustained in a substantially perpendicular position.

In testimony that I claim the foregoing as my invention, I have signed my name.

JULIEN STRANDERS.
